UNITED STATES PATENT OFFICE.

EDWARD H. ANGLE AND SPENCER R. ATKINSON, OF PASADENA, CALIFORNIA.

ORTHODONTIC IMPLEMENT.

Original application filed March 11, 1922, Serial No. 542,871, Patent No. 1,531,898, dated March 31, 1925.
 Divided and this application filed February 25, 1925. Serial No. 11,429.

Our invention relates particularly to that class of orthodontic implements that are shown and described in our application for United States Letters Patent, Serial Number 542,871, of which this is a division, and that are adapted to effect the adjustment of an arch-bar with respect to its terminal anchorages, and is especially designed for use in connection with the form of arch-bar and its cooperative terminal anchorages as disclosed in Letters Patent of the United States Number 1,398,761, granted to us November 29, 1921.

The principal objects of our invention are to provide an adjusting implement of such simplified construction that it may be readily applied to effect the adjustment of the arch-bar, and actuated with such delicacy by the mere contraction of the muscles of the hand of the operator, as to afford minimum discomfort to the patient, yet with such power and uniformity of action as to attain the desired stress in a positive manner upon the malposed teeth of the dental arch, which may be attached to said arch-bar for the purpose of correction of position.

Our invention comprehends an implement having relatively movable members that may be conveniently thrust into the mouth of the patient, and respectively engage the anchor as an abutment, and the arch-bar so that when caused to relatively approach, they effect the adjustment of said arch-bar with respect to said anchor, one of said members being formed to either engage the end of the arch-bar, or to engage its attached tang intermediate of its ends.

Other objects of our invention are to provide an adjusting implement that is so constructed and arranged as to contemporaneously effect the adjustment of the arch-bar and the automatic locking of said arch-bar with respect to its anchor in such a manner that it will be retained in its adjusted position when said implement is withdrawn therefrom.

Specifically stated, the form of our invention as hereinafter described, comprises an implement having relatively movable members pivoted together, one forming an abut-

ment arranged to bear against the end of the sheath of the anchor, and being bifurcated to permit the arch-bar to pass therethrough, and having a transverse groove arranged to guide the retaining tang of said arch-bar and to deflect it into its locking position, while the other member is provided with a projecting finger or prong forming a hook or claw arranged to engage the rear end of the tang on the arch-bar, so that when said pivoted members are actuated to cause the prong and abutment to approach each other, the arch-bar will be adjusted longitudinally with relation to the anchor sheath, and the retaining tang will be curled over, by the guide comprising the transverse groove, against the end of the anchor sheath to lock the arch-bar in its adjusted position.

Our invention also includes all of the various novel features of construction and arrangement as hereinafter more definitely specified.

In the accompanying drawings, Figure 1 is a plan view of a human dental arch showing the type of orthodontic regulating device, including an arch-bar and its anchorages, for which our orthodontic implement is particularly designed to adjust; Fig. 2 is a plan view, showing an orthodontic implement constructed in accordance with our invention, as applied to the arch-bar and its anchor, and in position to effect the adjustment of the same; Fig. 3 is a perspective view of the implement shown in Fig. 2; Fig. 4 is an enlarged fragmentary longitudinal sectional view taken centrally through the left-hand beak of the implement comprising the pliers shown in Fig. 2; Fig. 5 is a fragmentary elevational view showing the inner face of the beak shown in Fig. 4; Fig. 6 is an enlarged fragmentary elevational view of the inner face of the right-hand beak of the implement shown in Fig. 2; and Fig. 7 is a plan view similar to Fig. 2, but showing a fragment of the opposed beaks distended to engage the end of the arch-bar exterior to the sheath.

The tooth regulating appliance to which this invention is particularly applicable is indicated in a general way in Fig. 1 and in

cludes, together with associated parts, an anchor-bar 1, preferably consisting of a flattened wire having its intermediate portions arranged to be engaged with brackets 2 on suitably formed tooth-bands 3 which are attached to selected anterior teeth 4 of the dental arch, and its terminals engaged with the anchor-bands 5 which are secured to selected posterior or molar teeth 6.

10 The anchor-bands 5, as shown in Fig. 1, are of a well known construction, having the eye 7 at one end, and the threaded stem 8 at the other end extended through said eye 7 and adjusted therein to clamp the band to the tooth by means of the adjusting nut 9 threaded on said stem.

Each of said anchor-bands is provided with a tubular sheath 10, the hollow or bore 12 of which is preferably shaped to conform to and receive the terminal of the arch-bar suitably fitted therein for longitudinal adjustment.

The sheath 10, as best shown in Fig. 2, is provided with the slot 13, opening into the bore 12, and providing a keyway for the key or spline forming a tang 15, which is formed integrally with the arch-bar 1, being rigidly attached thereto toward the end of said arch-bar, and having that portion extended toward the medial region of the arch-bar, free to be deflected relatively thereto and bent, curled or otherwise distorted, to afford a retaining lock for maintaining the arch-bar in the position to which it may be adjusted.

As shown in Figs. 1 and 2, the spline forming the tang 15 on the arch-bar 1, terminates at its connected end, short of the end of said arch-bar, and thus affords a shoulder 16, which may be conveniently engaged to effect the longitudinal adjustment of said arch-bar 1 with respect to the anchor sheath 10.

The implement shown in Figs. 2 and 3 is especially designed to accomplish such adjustment of the arch-bar in its sheath, and to automatically effect the actuation of the tang, and comprises the pliers 20 having the pivoted handles 21 and 22 which when caused to approach, effect the consequent approach of their respective beaks 23 and 24.

The beak 23 serves as an abutment arranged to bear against the outer end of the sheath 10, while the beak 24 is provided with the prong or finger providing a claw 26 extended slightly toward the abutment beak 23, to form a hook which serves to engage the shoulder 16, to effect the forward adjustment of the arch-bar when said handles 21 and 22 are squeezed together to effect the relative approach of said beaks.

As shown in Figs. 3 and 6, the beak 23 has its free end bifurcated to form the slot 29 which serves as a guide for the arch-bar 1, as shown in Fig. 2, and said beak 23 also

has the transversely disposed slot 30 extended across the inner face of the beak 23 and adjoining but not crossing the slot 29, being so relatively associated that the bottom or floors of said slots 29 and 30 form a substantially square projecting corner 32.

The beak 24, as shown in Figs. 4 and 5, is provided with the pocket 33 in its inner face adjoining the prong 26, which, as shown in Fig. 7, is arranged to engage the end of the arch-bar 1, when the end of the tang 15 forming the shoulder 16 is in such position as not being available for engagement by the prong 26, and the arch-bar 1 may be thus adjusted until said shoulder 16 registers with the slot 13, as shown in Fig. 1 at the right hand side of the dental arch, and in Fig. 2.

It will be obvious that when the implement is engaged with the sheath, as shown in Fig. 2, and the prongs 23 and 24 are caused to approach, the arch-bar 1 will be guided longitudinally through the slot 29 while the tang 15 is so guided by the groove 30, as to be deflected laterally and thereby curled over, as shown, to form a retaining lock arranged to maintain said arch-bar in the position to which it is thus adjusted.

Our invention is advantageous in that the means of adjustment of the arch-bar 1, with respect to its anchor is not carried on the device which remains within the mouth of the patient, and therefore said arch-bar is not readily tampered with, without the knowledge of the operator, the adjusting implement, which in effect serves as a key, being retained by the operator, may be inserted in the mouth of the patient when desired, and engaged with the parts to be adjusted, such adjustment being effected by means actuated wholly exterior to the mouth of the patient.

We do not desire to limit our invention to the precise details of construction and arrangement as herein set forth, as it is obvious that various modifications may be made therein without departing from the essential features of our invention as defined in the appended claims.

Having thus described our invention, we claim:

1. An implement of the class described, comprising opposed relatively movable members respectively having an abutment provided with a guide arranged to direct an arch-bar provided with a tang longitudinally therethrough, and having means arranged to deflect said tang laterally from said arch-bar, and pivotally connected means arranged to effect the longitudinal movement of said arch-bar with respect to said guide.

2. An implement of the class described, comprising opposed relatively pivoted members respectively having an abutment provided with a guide arranged to longitudinally direct an arch-bar having a tang, and

having means arranged to relatively deflect said tang laterally from said arch-bar, and an opposed projection movable about the pivoted axis with respect to said abutment and including a prong and a pocket arranged to engage and progress said arch-bar with respect to said guide.

In witness whereof, we have hereunto set our hands the 18th day of February, A. D., 1925, and the 18th day of February, A. D., 1925, respectively.

EDWARD H. ANGLE.
SPENCER R. ATKINSON.
